United States Patent Office

Des. 183,403

Patented Aug. 19, 1958

183,403

COIN BANK

Adam T. Norwich, Cleveland, Ohio

Application October 17, 1957, Serial No. 48,144

Term of patent 14 years

(Cl. D34—11)

Fig. 1

Fig. 2

Fig. 3

Fig. 4

Fig. 5

I claim:

The ornamental design for a coin bank, substantially as shown.
